CLOSURE

Fritz S. Zaisser, Bronx, N. Y.

Application April 16, 1931, Serial No. 530,469

2 Claims. (Cl. 156—38)

This invention relates to closures, especially closures for windows of buildings, and particularly closures consisting largely of a sheet or sheets of pervious material supported by a skeleton 5 frame.

A principal object of this invention is the provision of a closure of the type described which will form a complete closure of an open window so that there will be no opportunity at any point 10 for insects of any considerable size to pass.

A further object of the invention is a closure of the type specified, so constructed that the pervious material forming the major portion thereof may be quite readily applied, renewed, or re- 15 placed.

A further object of the invention is the provision of a closure of the type specified which includes a plurality of parts, preferably two, in which the outer sliding section is slightly longer 20 than the inner section or sections, that is, if there are two sections, the outer section will be the longer, if there are more than two sections the sections will increase in length from the inner to the outer sections, proportionately, to the slope 25 of the window sill.

Other objects and advantages will appear as the description of particular physical embodiments selected to illustrate the invention progresses, and the novel features will be particularly 30 pointed out in the appended claims.

In describing the invention in detail, and the particular physical embodiments selected to illustrate the invention, reference will be had to the accompanying drawings and the several views 35 thereon, in which like characters of reference designate corresponding parts throughout the several views, and in which:

Figure 1 is a front elevation, of a closure embodying my invention, viewed from that side of 40 the closure which is on the inside when the closure is in place; Fig. 2 is a front elevation of the same closure as shown by Fig. 1, but viewed from that side of the closure which is outside when in place; Fig. 3, is a cross-sectional view on the plane indicated by the line III—III of Fig. 1, viewed 45 in the direction of the arrows at the ends of the line, and with fragments of a window casing shown in connection therewith; Fig. 4 is an enlarged detail view corresponding to the view as shown by Fig. 3; Fig. 5 is a cross-sectional view 50 of the device as shown by Fig. 1, on the plane indicated by the line V—V, viewed in the direction of the arrows at the ends of the line; Fig. 6, is an outside elevational view of a modified form 55 of window closure; Fig. 7 is a cross-sectional view

on the plane indicated by the line VII—VII of Fig. 6, viewed in the direction of the arrows at the ends of the line; Fig. 8 is a fragmentary detail view showing a connection between the inner and outer sections of a window closure; Fig. 9 is a detail view corresponding to Fig. 4 but showing a modified form of pervious material attaching means; Fig. 10 is a top plan view partly in section of a screen and window casing, illustrating the fitting of a wooden frame screen therein; Fig. 11 is an end view illustrating the manner in which the bottom of the screen of Fig. 10 contacts with the window sill.

In Fig. 1, a two part window closure has been illustrated. One of the parts has been designated 70 as a whole by A, the other by B. Each includes a substantially rectangular frame. The rectangular frame comprising the A section is composed of a bottom rail 1, side rails 2 and 3, and top rail 4. The member B includes the bottom rail 5, the 75 side rails 6 and 7, and the top rail 8. Although applicant has indicated the sections or parts A and B, as being composed of top and bottom rails and side rails, it is to be understood that applicant does not intend to exclude an integral construction in which the side rails and top and bottom rails will be formed of one continuous piece.

The two sections, frames, or slides A and B, of which A may be called the inside slide and B the outside slide, slide one on the other. In order to 85 provide for this sliding arrangement, applicant has provided inter-engaging tracks, partly on slide A and partly on slide B. This is most clearly shown by Fig. 5, in which 9 indicates the track attached to section B at the top and 10 designates the track attached to section A at the top, while 90 11 designates the track attached to section B at the bottom and 12 designates the track attached to section A at the bottom. By means of these inter-engaging tracks, the section A may slide on the section B so that the sections may be collapsed to the point where both are together but slightly longer than one alone, or may be so extended that the length of the extended sections is nearly equal to the sum of the lengths of each section, thus 95 providing for windows of different widths.

Each section as A and B is mainly a pervious flat material, such as 13, section A, and 14, section B. In order to maintain in place the pervious material, which may be woven wire or a 105 woven textile material, applicant provides various means, one of which is shown particularly in Fig. 5. In this view one construction shown, to wit, that in which a member or rod 15, of substantially circular cross-section, is attached by 110

any appropriate means, such as soldering or welding, to the bottom rail 5 of section B, and another rod 16 on the top rail 8 of section B; and a corresponding rod 17 at the bottom of section A; and a corresponding rod 18, shown in Fig. 1 on the top rail 4 of section A.

The pervious material, such as 13 and 14, is cut of the proper size, and then laid flat upon the section to which it is to be attached, then on each 10 of the rods such as 17, 18, 19, and 20 as shown in Fig. 1, a trough shaped retaining member is pushed down in place. These trough shaped members are designated 21, 22, 23, and 24', and are shown clearly in cross-section in Fig. 5, in 15 which 21 and 23 are most clearly shown on section A. This construction is such that the pervious material may be removed, or renewed, or replaced in case conditions necessitate a change. This is especially necessary in the case of window closures used as ventilators and covered with 20 a pervious material such as cotton cloth which becomes discolored and its pores filled with dust, so that at intervals it is necessary to remove, clean, and then replace it, or to remove and to 25 replace it with new material. With applicant's construction it is very easy to make the change.

Each of the slides or sections A and B have a shoulder member, as 24 and 25, attached thereto. These shoulder members are each designed to bear against the inside face of the bottom rail of the lower sash of a window. Their position in relation to the lower rail 26 of a window sash is clearly shown by Fig. 5. The rail has its lower face 27 in contact with the shoulder member 25 at the point 28 and the inside face contacts with the shoulder member 25 at the point 29. At the same time, the inside face of the lower rail 26 contacts with the shoulder member 24 at the point 30.

40 By reference to Figs. 1, 2, and 5 it will be seen that the section B, that is, the outside section is slightly longer than the section A, that is, the inside section, so that the closure is supported by the outside section B resting on the sill 31 as at the point 32.

45 By reference to Fig. 3 it will be seen that the section B has an end extension 33 to the side rail 7 which extension is bent toward the plane of the section A and has its end surface in a plane passing through the inside surface of the section A, as shown by Fig. 3, so that the extension 33 of section B rests against the front stop 34 of the window casing and is on a line with the surface of rail 2 of section A which rests against the front stop 35.

50 The construction of the screen as hereinbefore described is such that a preferred closure for a window space is provided. The section A of the screen by means of the rail 1, as best shown in Fig. 5, bears tightly against the shoulder 36 of the sill 31; the rail 5 bears tightly against the sill 31 along the line 32 so that along the entire bottom of the screen there is no opening through which insects may pass. The left hand edge of the screen as shown in Fig. 3 bears, by means of the rail 2, tightly against the front stop 35. The right hand end of the closure bears, by means of the extension 33, tightly against the stop 34. At the top of the screen the shoulder 25 bears against the lower rail 26 of the lower sash along the line 29, and section A bears against the rail 26 along the line 30. Along the four sides of the screen there is no opportunity for insects to pass. The pervious material 13 of section A is, of course, slightly separated from the pervious material 14

of section B, but the entrance of insects through the space designated 37 in Fig. 5 is prevented, as best shown in Fig. 3, by the pervious material contacting portion 38 of section B being turned over to contact with the pervious material 13 of section A, and the like portion 39 of rail 3 of section A is turned over so as to contact with the pervious material 14 of section B.

55 It is to be particularly observed that section B, that is, the outside section of the closure, extends down far enough below section A that its rail 5 rests tightly against the sill 31 and that it is held tightly against the sill 31 by the pressure of the sash, of which the lower rail is 26, bearing tightly against the shoulder 25 along the line 28. This construction insures a closure along the line 32, which is open on ordinary and well known screens, and also insures a stability to the closure, which is absent from ordinary closures and screens, because the ordinary closure or screen although having the lower rail of the sash resting on the outside section thereof has that outside section up above the sill and free therefrom, the screen resting upon the inner section, that is, the section corresponding to applicant's section A.

60 By reference to Figs. 1 and 2, it will be seen that the shoulder members 24 and 25 do not extend the full length of the sections to which they are attached, there being a cut out portion at 40 on section B, and another cut out portion at 41 on section A. These cut out portions are necessary because the shoulder members 24 and 25 must be constructed so as not to interfere with the front stops, as 34 and 35 as shown in Fig. 3. 65 The amount cut away is merely sufficient to allow enough of the rails as 2 and 7 to abut the front stops, as 34 and 35, so as to keep the screen properly in place and close the opening at these points.

65 By Fig. 6 a modified form of closure is shown. This modified form consists of two sections C and D comparable with B and A of Fig. 1. In this form, the rails as 42, 43, 44, and 45, and the corresponding rails upon sections D, are not mitered at the corners as in the form shown by Figs. 1 and 2, but are butt jointed, as at 46 and 47. This is done because the rails, such as 44, are formed with a projection 48 substantially, approximately circular in cross-section, as best 70 shown in Fig. 7. The mating rail on section D is likewise formed but, of course, reversely as shown in Fig. 7 with projection 49. A tie and slide member 50 is fitted into the projections 48 and 49 and due to its shape, somewhat like a 75 dumb-bell, it retains the sections close together and also furnishes a slide for one section to move relatively to the other.

80 In Fig. 8 a modified form of construction is shown in which the rails as 1 and 5 are pressed or rolled with projections 52 and 53 respectively 85 thereon over which members 15 and 17 are placed.

85 Fig. 8 also shows a modified form of inter-engaging rails between the sections as A and B. In this form a dovetail grooved member 54 is attached to a rail, as 1, and a dovetail tongue 55 is attached to a rail, as 5. The tongue 55 and the groove 54 inter-engage so that the two sections will not move relatively transversely, but may be slid longitudinally.

90 In Fig. 9 another method of attaching the pervious material to the closure sections is shown. In the form of closure as shown by Fig. 6, rails as 42, 43, 44 and 45 may have a portion as 56, shown in Fig. 9, on the inner edges thereof turned 95

upwardly as viewed in Fig. 6, that is, upwardly from the plane of the paper, and the rails such as 57, 58, 59, and 60 of section D may have the edges, as 61 of 57, as shown in Fig. 9 turned downwardly, that is, downwardly from the plane of the paper, as shown in Fig. 6. With such a construction the pervious material, as 62 and 63 in Fig. 9, may be attached to projections, as 56 and 61, by means of channels, as 64 and 65, which 10 when placed over the projections, as 56 and 61, will when the pervious material is therebetween fit so tightly that they will remain in place and securely hold the pervious material.

In Fig. 10 a closure has been illustrated formed 15 of two sections, E and F, which are of some considerable thickness, that is, they are not as thin as the ordinary sheet metal sections as shown in Fig. 1 to 9 inclusive. In such case a strip 65 is attached to one of the sections E, so that the 20 end corner of that section will be on a line with the line 66 of section F, so that both section F and section E will properly bear against the front stops 67 and 68. In order to have a closure of the form shown in Fig. 10 properly bear upon the sill 25 so that the section F will bear against the shoulder 69 of the sill 70 and the section E which is the outside section of the screen will properly bear upon surface 71 of the sill, it is necessary to bevel the lower surface of section F and the 30 bottom of section E, as shown in Fig. 11 at 72, so that the lower surface of F will not bear upon the surface 71 of the sill 70, but the closure will bear along the line 73, that is, along the inside line of the outside section E. By such construction 35 a closure, as one composed of sections E and F, provided with the shoulders, such as 24 and 25, as shown in Fig. 5, and bearing against the front stops 67 and 68, as shown in Fig. 10, would completely close the opening of the window in 40 which it is placed, because the inside section F would bear along the surface 69 of the sill 70, and the outside section E would bear along the line 73 on the surface 71 of the sill 70, thus completely closing the opening caused by the window 45 being moved upwardly, so that no insects may pass beyond the closure formed by the sections E and F.

Although I have particularly described a preferred form and other embodiments of my invention and explained the principle and mode of operation and construction thereof, nevertheless, I desire to have it understood that the forms selected are merely illustrative but do not exhaust the possible physical embodiments of the idea of means underlying my invention.

What I claim as new and desire to secure by Letters Patent of the United States, is:

1. In a closure, in combination: two covered frames slidingly cooperating, the two frames together being of a thickness less than the distance between the front and back stops for the lower sash of a window, one of said frames extending downwardly farther than the other whereby it may be made the outside frame of the closure and close the space between it and the sill of a window opening in which it is placed and means at the top of each frame whereby no spaces exist between either frame and the lower rail of the lower sash of a window in which the closure is placed.

2. In a closure, in combination: two frames, each including a top, a bottom, and two side rails, the bottom rail of one frame being slightly wider than the bottom rail of the other frame; means positioned between the frames and cooperating with each frame whereby one frame is slidingly attached to the other frame; pervious material positioned on each frame; means, including rod-like members attached to the rails and trough-like members adapted to be pushed in place thereon for maintaining the pervious material in place; a pervious material contacting portion on a side rail of each frame for contacting the pervious material of the other frame; an end extension on one side rail of one frame for contact with a front stop of an opening in line with the other frame; shoulder members attached to the top rail of each frame formed to bear against the inside face of the lower rail of a window sash positioned in the opening where the closure is used, said shoulder members each having a cut away portion at their outside ends to receive the front stops of an opening.
